UNITED STATES PATENT OFFICE.

ROBERT A. REID, OF MEDFORD, MASSACHUSETTS.

AUXILIARY AIR-INLET DEVICE FOR INTERNAL-COMBUSTION ENGINES.

Application filed June 4, 1923. Serial No. 643,239.

This invention relates to a heater and vaporizer for the fuel used in an internal combustion engine and the object thereof is to provide such a device which will thoroughly heat and entirely vaporize the fuel.

A further object of the present invention is to provide such a heater and vaporizer which is adjustable to give different desired degrees of heat.

10 A further object of the invention is to provide such a heater which is cheap to manufacture and easy to apply to the engine.

15 A further object of the invention is to provide such a heater which will admit heated fresh air to the intake manifold of the internal combustion engine but which will prevent water from entering the manifold.

20 Other objects and features of the invention will more fully appear from the following description and the accompanying drawings and will be particularly pointed out in the claim.

25 The drawings illustrate a preferred form of construction adapted for use in a heater and vaporizer for internal combustion engines and embody the broad principles of the invention.

In the drawings:

30 Fig. 1 is an elevation of the invention applied to an internal combustion engine;

Fig. 2 is an end view of the invention showing the exhaust pipe of the engine in section;

35 Fig. 3 is an elevation of the heater and vaporizer showing one way in which it may be adjusted.

The device which forms the subject matter of the present invention is intended to be 40 applied to the usual type of internal combustion engine designated generally at 1 and which has an exhaust manifold 2, an intake manifold 3, branching at 4 to connect with the engine cylinders, and a carburetor 5 supplied with liquid fuel through a pipe 6.

As illustrated herein the device constituting the invention consists of a tube 7 having at one end a heat conducting coil 8 fastened against the exhaust manifold and 50 having the other end 9 extending into the intake manifold whereby the suction of the engine will draw air through the coil where it is heated and into the intake manifold where it heats and vaporizes the fuel. The 55 tube is preferably a flexible metallic tube adapted to be bent into coils, with one end

of the tube bent, as shown in the drawings, into a heat conduction coil and the other end extending into the intake manifold. The convolutions of the heat conducting 60 coil are so arranged as to produce a flat coil fitting against and curved where necessary to conform to the contour of the exhaust manifold. The coil may be fastened against the exhaust manifold in any desired position but in order to prevent any water, which may fall on the tube while the car is being washed or is standing in the rain, from entering the tube the coil is preferably fastened against the exhaust manifold 65 with the open end of the tube within the heating coil projecting downwardly as shown in the drawings. Although the end of the pipe which enters the intake manifold may stop as soon as it goes through the wall of said manifold, it is desirable that the end extend inside of the intake manifold to the point where the manifold branches to connect with the engine cylinders. With this construction the tube forms 70 a part within the manifold which is always highly heated and immediately vaporizes any fuel which comes from the carburetor as liquid spray.

In order to easily apply the invention to the engine a spacing member 10 is provided for insertion between the carburetor and the intake manifold and the end 9 of the tube extends through said spacing member into the intake manifold. The spacing member 75 may be held in place in any desired manner but it preferably has flanges 11 provided with holes 12 which register with corresponding flanges and holes on the adjacent portions of the carburetor and intake manifold, and bolts extend through the holes in the flanges of the carburetor, spacing member, and intake manifold to retain the parts in the position shown in Fig. 1. Gaskets 13

80 may be inserted on either side of the spacing member to provide a tight joint. By the use of the spacing member the entire device may be assembled in the shop where it is made and applied to the engine on which it is to be used without tapping the intake manifold or any other part of the engine and the only fittings which are necessary in applying the device are bolts which are long enough to extend through all of the flanges above mentioned and a means to fasten the heating coil against the exhaust manifold. Such means is preferably a band 85 90 95 100 105 110

14 which extends around the exhaust manifold and the heating coil and has its ends adjustably clamped together by means of a screw 15 passing through ears which are 5 formed on the ends of the band.

The device is adjustable to give different degrees of heat. When the device is made up as shown in Figs. 1 and 2 of the drawings it is giving a medium amount of heat. In 10 order to give less heat the coil may be removed from the position shown in full lines in Fig. 1 against that part of the exhaust manifold which gets the heat from two cylinders and fastened in the position shown 15 in dotted lines in Fig. 1 where it is clamped against that part of the exhaust manifold which only receives the heat from one cylinder. If the device still heats the fuel to too 20 high a degree, one or more turns may be taken off of the heating coil and formed 25 into a cooling coil 16 intermediate between the heating coil and the point where the tube enters the intake manifold. If a maximum heating effect is desired the coil may be 30 clamped on that part of the exhaust manifold which is heated by the exhaust gases from all of the cylinders of the engine. The flat shape of the coil enables it readily to be slid along the face of the manifold and se-

35 cured at any desired point. The device may be applied to any engine. The heating coil may be fastened against any hot part of the engine and the tube may be lengthened to accommodate such changes 40 in position. The device is particularly useful because the amount of air which is sucked in through the coil and the amount of heat which is given off by the end of the tube which is within the intake manifold is determined by the working conditions of the 45 engine. The faster the engine goes, the greater is the suction within the intake manifold and consequently the greater is the amount of fuel drawn through the intake

50 manifold. The heater and vaporizer meets this condition because the amount of air passing through the coil is determined by the suction on the intake manifold and the temperature of the heating coil is determined by the temperature of the exhaust manifold which in turn is determined by the number of explosions and the speed of the engine. Thus the device is self-regulating. It has been found that the use of the invention lessens the deposit of carbon in the cylinders 55 of the engine and since it is assured that the fuel drawn into the cylinder is in the gaseous state it prevents the possibility that liquid gasoline will leak from the interior of the cylinder down past the piston rings into the crank case and thin the lubricating oil.

Although a particular and preferred form of the invention has been described modifications may be made and the invention is to be construed as broadly as the limitations 60 in the claim, taken in conjunction with the prior art, may allow.

Having thus described the invention what is claimed as new and desired to be secured by Letters Patent is:

An auxiliary air inlet device for internal combustion engines comprising a length of pipe, for conveying air and having one end formed into a flat coil of a shape to rest against the outside face of the exhaust pipe 75 of an internal combustion engine, a strap to encircle the exhaust pipe and coil and secure the latter in place, said pipe extending from the coil downwardly and then upwardly, and a member adapted to be inserted between the 80 carbureter and the intake pipe and having an opening therethrough, and through one wall of which the end of said pipe extends, both ends of the pipe being open.

In testimony whereof, I have signed my 85 name to this specification.

ROBERT A. REID,
